CLAIM

The ornamental design for a canopy for a ceiling fan, as shown and described.

DESCRIPTION

FIG. 1 is a bottom perspective view of a canopy for a ceiling fan showing my new design;

FIG. 2 is a top perspective view of the canopy of FIG. 1;

FIG. 3 is a top view of the canopy of FIG. 1;

FIG. 4 is a front side view of the canopy of FIG. 1, with rear, right, and left side views being mirror images thereof; and,

FIG. 5 is a bottom view of the canopy of FIG. 1.

The broken lines showing a ceiling fan illustrates the environment of the canopy for a ceiling fan and form no part of the claimed design.
